UNITED STATES PATENT OFFICE.

LYMAN V. GRAHAM, OF KANSAS CITY, MISSOURI.

STANCE INDICATOR FOR GOLF.

Application filed October 2, 1922. Serial No. 591,854.

To all whom it may concern:

Be it known that I, LYMAN V. GRAHAM, a citizen of the United States, and resident of Kansas City, county of Jackson, State of Missouri, have invented a certain new and useful Improvement in Stance Indicators for Golf, of which the following is a complete specification.

This invention relates to golf stance indicators to indicate the correct placing of the feet with regard to the position of the ball in the teaching of golf, and may also be used for practice purposes in learning the exact stance for the most satisfactory results in playing any particular shot.

A further object is to produce a golf stance indicator of such nature that it may be used to accurately follow out written instructions as to the correct position for the feet in playing a particular stroke with a particular club.

A still further object is to produce a device of the character set forth which may be readily and easily dismantled for storage or transport.

The chief objects are accomplished, as will hereinafter appear, by accurately determining the exact position of the feet of the player and the ball with regard to the angle of flight or direction in which it is intended to drive the ball.

With the objects named in view, the invention consists in certain novel and useful features of construction and organization of parts as hereinafter described and claimed; and in order that it may be fully understood, reference is to be had to the accompanying drawing, in which:

Figure 1 is a perspective view of a golf stance indicator embodying the invention;

Figure 2 is a side elevation of the same;

Figure 3 is an enlarged top plan view of the head of the device partly broken away to disclose parts otherwise hidden;

Figure 4 is an enlarged top plan view of the connection between one of the sliding arms of the stem of the device;

Figure 5 is a section on the line V—V of Figure 4; and

Figure 6 is a perspective view of a modified form of the device.

In the said drawing, where like reference characters identify corresponding parts in all of the figures, 1 indicates the stem or main indicating member of the stance indicator and said stem is numbered consecutive-

ly in inches or other units from one end to the other. Rigidly secured at the end of the stem where the graduations begin is a T-shaped head 2 held in position by means of rivets 3 and securely braced by means of downwardly and inwardly extending flanges 4 partially embracing the stem, as clearly shown by the drawing. The free ends of the cross head 2 are formed with downwardly and inwardly extending flanges 5 for a purpose which will hereinafter appear.

The extremity of the stem is recessed for the reception of a spring catch 6 formed with a lug 7 and held in position at one end by means of a screw 8, the other end being free for sliding movement in the recess. The catch 6 is adapted to lock a transverse cross head 9 in position on the end of the stem by coming into locking engagement with a recess 10 formed midway the length of the inner edge of the cross head, as will be readily understood, said cross head being slidably received within the flanges 5 of the member 2. The cross head 9 is consecutively numbered from the left to the right in the same units as that of the stem.

A pair of parallel longitudinal slots 11 are formed in the upper face of the stem, and the lower face is provided with similar slots 12. Adapted for sliding longitudinal movement along the stem and projecting in opposite directions are a pair of T-shaped members 13 provided with suitable flanged extremities 14 and 15 for engagement with the slots 11 and 12 respectively, the free ends of the members 13 being bent downwardly and inwardly to form flanges 16, and being cut away centrally and the cut out portions bent downwardly and inwardly to form flanges 17.

Fitted within the flanges 16 and 17 of each of the T-shaped members 13 are oppositely projecting arms 18 held rigidly in position by means of rivets 19. Each of the arms 18 is consecutively numbered from the stem outwardly in the same units as said stem, and may be slid longitudinally of the stem and independently of the other arm as found desirable, as will hereinafter appear.

From the construction above described it will be apparent that when it is desired to dismantle the device for storage or transportation, the head member 9 may be removed from position and that the wings 18 may be slid longitudinally of the stem until disengaged.

The device as indicated by Figure 6 is

preferably made of small tubes and is provided with a single arm 18 which may be rotated around the stem to either side thereof for indicating the position of the right or 5 left foot, as will hereinafter appear. It is otherwise similar in all respects to the device above described.

The use of a device for the teaching of a correct stance is as follows:—For example, 10 the following directions are given:—Ball 6, Left 16—14, Right 21—11, which interpreted, means that the ball shall be placed in the position indicated by the arrow opposite the "6" of the head piece, the toe of 15 the left foot must be placed in the position indicated by the arrow opposite the "14" of the left wing, and the toe of the right foot opposite the "11" of the right wing, it being understood that the wings will be 20 preliminarily positioned opposite the "16" and "21" respectively of the stem.

For use in practice in the correction of faults, the player can make use of the indicator for determining his common position 25 which results in a slice, for example, and then through experimentation with the device may determine the exact stance he should assume for the correction of the fault.

30 In the use of the device as illustrated in Figure 6, it will be apparent that the player must determine and mark the position of one foot and then rotate the arm 18 and carry out the operation with the other foot.

35 When the player using the stance indicator is actually going to attempt a practice drive or play, the position of the ball and the toe of each foot will be indicated on the ground by means of a mark or a match laid 40 on the ground, the indicator is now removed and the player tees his ball and takes his stance in accordance with the points preliminarily determined, as will be readily 45 understood.

50 The above examples are given merely as indicatory of some of the uses to which the indicator may be put, but it will be evident that it may be used in many different ways by an experienced player.

55 In connection with the use of the invention, it is highly important that the cross-piece of the stem shall always be placed coinciding with the line of flight or direction in which it is desired to drive the ball, as in giving directions for the use of the instrument, the predetermined line of flight will always be employed as the basis for the computation of the relative positions 60 of the ball and feet of the player.

65 From the above description, it will be apparent that I have produced a device of the character set forth which possesses all of the features of advantage set forth as desirable, and while I have described and 70 claimed the preferred embodiment of the

same, I reserve the right to make all changes properly falling within the spirit and scope of the appended claims.

I claim:

1. A stance indicator, comprising a stem 70 having linear measurement indicated thereon, said graduations commencing at one end of said stem and serving as a guide for the user in assuming a position the required distance from the said end of the stem; a cross head secured to the said end of the stem at right angles thereto, and provided with measurement marks as a guide in locating a golf ball relative to said cross head and stem, and an arm paralleling the cross head and slidably connected to the stem for adjustment laterally toward and from the cross head, and provided with measurement marks as a guide for the positioning of a foot of the user at the distance desired 80 from the stem.

2. A stance indicator, comprising a stem having linear measurement indicated thereon, said graduations commencing at one end of said stem and serving as a guide for the user in assuming a position the required distance from the said end of the stem; a cross head secured to the said end of the stem at right angles thereto, and provided with measurement marks as a guide in locating a golf ball relative to said cross head and stem, an arm paralleling the cross head and slidably connected to the stem for adjustment laterally toward and from the cross head, and provided with measurement marks as a guide for the positioning of a foot of the user at the distance desired from the stem; 90 a second arm paralleling the cross head and slidably connected to the stem for adjustment laterally toward and from the cross head, and provided with measurement marks as a guide for the positioning of a foot of the user at the distance desired from the stem; and a third arm 95 paralleling the cross head and slidably connected to the stem and projecting laterally therefrom in the opposite direction to the first-named arm and independently slidably on the stem, and provided with measurement marks as a guide for the positioning of the other foot 100 of the user.

3. A stance indicator, comprising a stem having linear measurement indicated thereon, said graduations commencing at one end of said stem and serving as a guide for the user in assuming a position the required distance from the said end of the stem, a cross head detachably secured at an intermediate point in its length, to said stem and extending at right angles to the latter, and provided with measurement marks as a guide in locating the desired position for a golf ball, relative to the cross head and stem, and an arm paralleling the cross head and slidably connected to the stem for adjustment laterally toward and from the cross head, and provided with measurement marks as a guide for the positioning of a foot of the user at the distance desired from the stem.

4. A stance indicator, comprising a stem

havning linear measurement indicated thereon, said graduations commencing at one end of said stem and serving as a guide for the user in assuming a position the required 5 distance from the said end of the stem, a cross head detachably secured to the said end of the stem at right angles thereto, and provided with measurement marks as a guide in locating the desired position for a 10 golf ball relative to said cross head and stem, an arm paralleling the cross head and projecting laterally from and mounted slidably on the stem for movement toward and

from the cross head, and a second arm 15 parallel to the cross head and slidably secured to the stem for movement toward and from the cross head and projecting in the opposite direction from the said stem to the first-named arm, said arms having measurement marks as a guide for the positioning of the feet of the user at the requisite distance from and at opposite sides 20 of said stem.

In witness whereof I hereunto affix my signature.

LYMAN V. GRAHAM.
